UNITED STATES PATENT OFFICE.

GEORGE S. LEWIS, OF CHICOPEE FALLS, MASSACHUSETTS, ASSIGNOR TO J. STEVENS ARMS & TOOL COMPANY, OF CHICOPEE FALLS, MASSACHUSETTS, A CORPORATION OF MASSACHUSETTS.

MAGAZINE-GUN.

1,041,109.

Specification of Letters Patent. Patented Oct. 15, 1912.

Application filed March 28, 1912. Serial No. 686,916.

To all whom it may concern:

Be it known that I, GEORGE S. LEWIS, a citizen of the United States, residing in Chicopee Falls, Hampden county, State of Massachusetts, have invented certain new and useful Improvements in Magazine-Guns, of which the following is a specification, reference being had to the accompanying drawing, which forms a part hereof.

10 This invention relates to so-called "pump guns," in which the operations of ejecting the empty cartridge shell, placing a fresh cartridge in the chamber of the barrel, and cocking the gun in readiness for firing are usually accomplished by longitudinal reciprocating movements of a fore-end or grip-piece which slides on a magazine tube below the barrel and is connected to the breech mechanism by a slide-bar. The grip-piece 20 or fore-end necessarily has a predetermined range of movement in order that the several operations may be accomplished and the guide or magazine tube upon which it moves necessarily has a certain definite length.

25 Ordinarily the guide or magazine tube has a length sufficient to hold five or more cartridges and it is the special object of this invention as applied to the construction shown to provide means to limit the number 30 of cartridges which it is possible to place in the magazine while retaining the length of the magazine tube or the guide for the fore-end or grip-piece required for the proper operation of the gun, without making necessary a reorganization and reconstruction of the gun.

The general object of the invention, however, is to provide means for limiting the number of cartridges which it is possible to 40 place in any form of magazine without changing otherwise the pattern of the gun.

The invention will be more fully explained hereinafter with reference to the accompanying drawing in which it is illustrated 45 and in which—

Figure 1 is a view in side elevation of a shot gun of the type referred to. Fig. 2 is a partial view of the same on a larger scale, partly in elevation and partly in longitudinal section, illustrating the application of the invention thereto.

The gun, whether rifle or shot gun, to which the invention is shown as applied may be of any usual or suitable construction,

comprising a barrel *a*, a receiver or frame *b*, 55 a stock *c*; a magazine tube *d*, a fore-end or grip-piece *e* arranged to slide on the magazine tube *d*, and a slide bar *f* through which the movement of the grip-piece *e* is communicated to the breech mechanism. The 60 gun is shown in Fig. 2 as limited to two shots, one cartridge *g* being shown in position in the chamber *d* of the barrel and another cartridge *g* being shown in position in the rear end of the magazine tube *d* in 65 readiness to be pushed out of the same by the spring follower or cartridge feeding spring and transferred by the breech mechanism to the chamber of the barrel. The spring follower is also shown as of usual construction, 70 comprising a long coiled spring *h* placed within the magazine tube *d*, a cap *h* which is free to slide within the magazine tube and receives the end of the spring *h*, abutting against the forward end of the cartridge *g*, 75 and an abutment *h* for the forward end of the spring *h*, such abutment serving both as a closure for the forward end of the magazine tube *h* and as a bracket by which the forward end of the magazine tube *d* is fastened to the under side of the barrel, as by 80 a screw *h*. Within the magazine tube *d* and within the coils of the spring *h*, is placed a rod *i* which supports the spring *h* and also forms a stop to limit the forward movement 85 of the follower cap *h*. Obviously this rod or transformer may be of any desired length, according to the number of cartridges which are to be inserted in the magazine tube. As shown, the rod is of such 90 length as to permit only one cartridge to be inserted in the magazine tube so that, with one cartridge in the chamber of the barrel, the gun becomes a two-shot gun.

The device can be applied readily to existing guns without requiring modification in their structure and accomplishes its intended purpose without interfering in any manner with the proper operation of the gun.

I claim as my invention:—

1. In a magazine gun, the combination of a barrel, a receiver, a magazine tube, a grip-piece arranged to slide on the magazine tube, a slide bar, a closure at the forward end of the magazine tube, a spring follower 105 within the magazine tube, and a removable stop, independent of the said closure and the said follower and arranged between the two

100

105

to limit the forward movement of the spring follower independently of the movement of the grip-piece.

2. In a magazine gun, the combination of 5 a barrel, a receiver, a magazine tube, a grip-piece arranged to slide on the magazine tube, a slide bar, a spring follower arranged within the magazine tube and comprising a long spiral spring and a cupped cap, and a rod 10 interposed between the forward end of the magazine tube and the cap of the follower to limit the forward movement of the cap and to support the spring.

3. In a firearm, the combination with the 15 tubular magazine and cap thereof, of a spring-actuated cartridge follower longitudinally movable in said magazine, and a removable transformer located within the said magazine tube and having a bearing at the 20 forward end against said cap and adapted at its rear end to limit the forward movement of the cartridge follower.

4. In a firearm, the combination with the 25 tubular magazine and cap thereof, of a cartridge follower located in said magazine, a spring within said magazine and tending to force the follower rearward, and an independently formed rod located within the 30 said spring and having a bearing at the forward end against the magazine cap and adapted at its rear end to be engaged by the said cartridge follower whereby the forward movement of the cartridge follower is positively arrested.

35 5. In a magazine gun, a tubular magazine closed at one end, a cartridge feeding spring and follower therein, and a removable stop

independent of the magazine and the follower and arranged between the follower and the closed end of the magazine to limit 40 the number of cartridges that may be placed therein by standing in the path thereof.

6. In a magazine gun, a tubular magazine closed at one end, a coiled cartridge feeding spring and follower therein, and a removable stop independent of the magazine and the follower and arranged in the follower and the closed end of the magazine to limit 45 the number of cartridges that may be placed therein by standing in the path thereof.

7. In a magazine gun, a tubular magazine, a coiled spring therein, a follower slidable in the magazine and movable by said spring, a removable plug at one end of the magazine, and a removable stop independent of 50 the follower and the plug and arranged in the magazine between the follower and the plug to limit the range of movement of the follower.

8. In a magazine gun, a tubular magazine, 55 a coiled spring therein, a follower slidable in the magazine and movable by said spring, a removable plug at one end of the magazine, and a removable stop independent of the follower and the plug and arranged in 60 the magazine between the follower and the plug, said stop being in the form of a rod located within the coils of the spring.

This specification signed and witnessed this 20th day of March A. D., 1912.

GEORGE S. LEWIS.
